UNITED STATES PATENT OFFICE.

SIDNEY O. BIGNEY, OF ATTLEBORO, MASSACHUSETTS.

FOB-CHAIN.

SPECIFICATION forming part of Letters Patent No. 727,883, dated May 12, 1903.

Application filed January 31, 1903. Serial No. 141,228. (No model.)

To all whom it may concern:

Be it known that I, SIDNEY O. BIGNEY, a citizen of the United States, residing at Attleboro, in the county of Bristol and State of Massachusetts, have invented certain new and useful Improvements in Fob-Chains, of which the following is a specification.

My invention relates to ornamental fob-chains, and is primarily designed to insure the attached watch against theft or accidental disengagement from the pocket or hand of the wearer. Further objects and advantages will be disclosed in the following description, and those features upon which protection is desired are defined in the appended claims.

In the accompanying drawings, which form a part of the specification, and wherein like letters of reference indicate like parts throughout the views, Figure 1 is a front elevation of my safety fob-chain engaged with a pocket, showing the connecting-chain and attached watch in broken outline; Fig. 2, a side elevation of the fastener open or in disengaged position; Fig. 3, a rear elevation of the same with adjacent parts broken away, and Fig. 4 a central vertical section of the fastener and adjacent parts in closed position engaging a pocket or belt.

My novel device is illustrated in connection with a vest or waist A; but its use is obviously as advantageous in connection with belts and other forms of wearing-apparel, and this diversity of application or adaptability is a noticeable advantage.

The fob *a* is preferably provided with the usual ornamented face and is pendent from a rearwardly-directed flat hook or lapping member *b*. This hook embraces the fastening means, which may be of any convenient construction; but said hook is independent of the fastening means. An advantageous form consists of the arched plate *c*, embraced by the hook or lapping member *b*, provided with an opening through its rear face, wherein is pivoted a lever *d*, with a short extension *e* disposed at an angle to the lever portion. The extension *e* has a central projection *i*. Fixed to the inner surface of the plate *c* is an arched flat spring *m*, with its free portion normally braced against the slotted portion of the plate *c*. This spring is provided with a vertical slot *n*, sufficiently broad to allow

the projection *i* to travel therein when the lever *d* is operated. The inner face of the spring has prongs *o* to insure firm engagement with the contacting fabric.

Attached to the free extremity of the plate member *c* of the hook or lapping member is a guard or connecting chain *p*, terminating in a swivel *r* or the other engaging means for the watch, locket, or other article *s* intended for use with the chain.

The operation of my device is obvious. The hook or lapping member *b*, with its auxiliary fastening means, is slipped over the upper margin of the pocket *t* and is engaged therewith. In this case the engagement is effected by raising the lever *d*, thereby forcing the free end of the spring *m* toward the fixed end thereof, as shown in Fig. 4. This engagement not only permanently fixes the position of the fob, but guards the watch against disengagement. The chain *p*, however, is of sufficient length to allow the watch to be withdrawn and consulted, while not so long as to cumbrously fold in the pocket.

My invention has the advantage of applicability to belts, which, as is well known, are provided with no means for receiving the bar of the guard-chain.

Having thus described my invention, what I claim as new, and desire to secure by Letters Patent, is—

1. In an article of the class described, the combination of a clasp, a hook independent of said clasp and adapted to be held in engagement therewith, and means for connecting a fob to said hook.

2. A device of the character described, embodying an inverted substantially U-shaped clip adapted to be secured to the garment, means for securing the watch to said clip, an independent lapping member adapted to engage over the bend of the clip, and means for attaching the fob to said lapping member.

3. A device of the character described, embodying an inverted substantially U-shaped clip adapted to be secured to the garment, means for securing the watch to said clip, an independent lapping member adapted to engage over the bend of the clip, connections between the lapping member and fob, and means for securing said lapping member in position.

4. A device of the character described, embodying an inverted substantially U-shaped clip, a substantially U-shaped spring secured within the clip, teeth formed on the spring, 5 a lever secured on the clip and engaging the spring to cause said teeth to engage in the garment, means for connecting the watch to the clip, and an independent lapping member to which the fob is attached adapted to

engage over the bend of said clip, said lapping member being held in place by said lever when the latter is in its closed position. 10

In testimony whereof I have affixed my signature in presence of two witnesses.

SIDNEY O. BIGNEY.
